2-(CYCLOALIPHATIC-ALKYL-AMINOMETHYL)-BENZODIOXANES

Lincoln Harvey Werner, Summit, N.J., assignor to Ciba Corporation, New York, N.Y., a corporation of Delaware
No Drawing. Filed Apr. 30, 1963, Ser. No. 276,993
12 Claims. (Cl. 260—340.3)

The present invention relates to 1,4-benzodioxane derivatives. More particularly, it concerns 2-aminomethyl-1,4-benzodioxanes of the formula

in which R_1 represents a 2-(1,4-benzodioxanyl) radical, n stands for a whole number from one to seven, and R_2 represents a cycloaliphatic radical, or salts of such compounds, as well as process for the preparation thereof.

A 2-(1,4-benzodioxanyl) group R_1 is particularly a group of the formula

in which R_a stands primarily for hydrogen, but may also represent an aliphatic radical, such as lower alkyl, e.g. methyl, ethyl, n-propyl, isopropyl, n-butyl, isobutyl, secondary butyl and the like, and Ph represents a 1,2-phenylene (o-phenylene) radical, such as 1,2-phenylene or 1,2-phenylene substituted by one or more than one substituent, which may be attached to any of the four positions available for substitution in a 1,2-phenylene radical. Substituents attached to the 1,2-phenylene radical are, for example, an aliphatic hydrocarbon radical, such as lower alkyl, e.g. methyl, ethyl, n-propyl, isopropyl, n-butyl and the like, hydroxyl, etherified hydroxyl, particularly lower alkoxy, e.g. methoxy, ethoxy, n-propoxy, isopropoxy, n-butoxy and the like, as well as lower alkenyloxy, e.g. allyloxy, 2-methyl-allyloxy and the like, lower alkylene-dioxy, e.g. methylenedioxy, 1,1-ethylenedioxy and the like, cycloalkyloxy, in which cycloalkyl has from three to eight, preferably from five to six, carbon atoms, e.g. cyclopentyloxy, cyclohexyloxy and the like, carbocyclic aryloxy, such as monocyclic carbocyclic aryloxy, e.g. phenoxy and the like, carbocyclic aryl-aliphatic etherified hydroxyl, such as monocyclic carbocyclic aryl-lower alkoxy, for example, phenyl-lower alkoxy, e.g. benzyloxy, 1-phenylethoxy, 2-phenylethoxy and the like, etherified hydroxyl, especially halogeno (representing hydroxyl esterified by a hydrohalic acid), e.g. fluoro, chloro, bromo and the like, trifluoromethyl, mercapto, etherified mercapto, such as lower alkyl-mercapto, e.g. methylmercapto, ethylmercapto and the like, nitro, amino, such as N,N-di-lower alkyl-amino, e.g. N,N-dimethylamino, N-ethyl-N-methyl-amino, N,N-diethylamino and the like, or N-acylamino, such as N-lower alkanoyl-amino, e.g. N-acetylamino, N-propionylamino, N-pivaloylamino and the like, or N-carbocyclic aroyl-amino, e.g. N-benzoylamino and the like, or particularly acyl, such as, for example, lower alkanoyl, e.g. acetyl, propionyl, butyryl, isobutyryl, pivaloyl and the like, as well as carbocyclic aroyl, such as monocyclic carbocyclic aroyl, e.g. benzoyl and the like, carbocyclic aryl-lower alkanoyl, such as monocyclic carbocyclic aryl-lower alkanoyl, for example, phenyl-lower alkanoyl, e.g. phenylacetyl and the like, or any other analogous, suitable substituent.

Substituted 1,2-phenylene groups are, for example, aliphatic substituted-1,2-phenylene, such as lower alkyl-1,2-phenylene, e.g. methyl-1,2-phenylene (such as 3-methyl-1,2-phenylene, 4-methyl-1,2-phenylene, 4,5-dimethyl-1,2-

2

phenylene and the like), ethyl-1,2-phenylene (such as 4-ethyl-1,2-phenylene and the like), n-propyl-1,2-phenylene (such as 4-n-propyl-1,2-phenylene and the like), isopropyl-1,2-phenylene (such as 3-isopropyl-1,2-phenylene and the like), or any other analogous lower alkyl-1,2-phenylene radical, hydroxy-1,2-phenylene (such as 3-hydroxy-1,2-phenylene, 4-hydroxy-1,2-phenylene and the like), etherified hydroxy-1,2-phenylene, such as lower alkoxy-1,2-phenylene, e.g. methoxy-1,2-phenylene (such as 3-methoxy-1,2-phenylene, 4-methoxy-1,2-phenylene, 3,4-dimethoxy-1,2-phenylene and the like), ethoxy-1,2-phenylene (such as 3-ethoxy-1,2-phenylene, 4-ethoxy-1,2-phenylene, 3,6-diethoxy-1,2-phenylene and the like), n-propoxy-1,2-phenylene (such as 4-n-propoxy-1,2-phenylene and the like), isopropoxy-1,2-phenylene (such as 3-isopropoxy-1,2-phenylene and the like), n-butoxy-1,2-phenylene (such as 4-n-butoxy-1,2-phenylene and the like), or any other analogous lower alkoxy-1,2-phenylene radical, lower alkenyloxy-1,2-phenylene, e.g. allyloxy-1,2-phenylene (such as 3-allyloxy-1,2-phenylene, 4-allyloxy-1,2-phenylene and the like), or any other analogous lower alkenyloxy-1,2-phenylene radical, lower alkylene-dioxy-1,2-phenylene, e.g. methylenedioxy-1,2-phenylene (such as 3,4-methylenedioxy-1,2-phenylene and the like), or any other analogous lower alkylene-dioxy-1,2-phenylene radical, cycloalkyloxy-1,2-phenylene, in which cycloalkyl has from three to eight, preferably from five to six carbon atoms, e.g. cyclopentyloxy-1,2-phenylene (such as 3-cyclopentyloxy-1,2-phenylene and the like), cyclohexyloxy-1,2-phenylene (such as 3-cyclohexyloxy-1,2-phenylene and the like) or any other analogous cycloalkyloxy-1,2-phenylene radical, monocyclic carbocyclic aryloxy-1,2-phenylene, e.g. phenoxy-1,2-phenylene (such as 3-phenoxy-1,2-phenylene and the like) or any other analogous monocyclic carbocyclic aryloxy-1,2-phenylene radical, monocyclic carbocyclic aryl-lower alkoxy-1,2-phenylene, such as phenyl-lower alkoxy-1,2-phenylene, e.g. benzyloxy-1,2-phenylene (such as 3-benzyloxy-1,2-phenylene, 4-benzyloxy-1,2-phenylene and the like), 2-phenylethoxy-1,2-phenylene [such as 3-(2-phenylethoxy)-1,2-phenylene and the like] or any other analogous monocyclic carbocyclic aryl-lower alkoxy-1,2-phenylene radical, esterified hydroxy-1,2-phenylene, particularly halogeno-1,2-phenylene, e.g. fluoro-1,2-phenylene (such as 3-fluoro-1,2-phenylene, 4-fluoro-1,2-phenylene and the like), chloro-1,2-phenylene (such as 3-chloro-1,2-phenylene, 4-chloro-1,2-phenylene, 4,5-dichloro-1,2-phenylene, 3,4,5,6-tetrachloro-1,2-phenylene and the like), bromo-1,2-phenylene (such as 4-bromo-1,2-phenylene, 3,6-dibromo-1,2-phenylene and the like), or any other analogous halogeno-1,2-phenylene or esterified hydroxy-1,2-phenylene radical, trifluoromethyl-1,2-phenylene (such as 4-trifluoromethyl-1,2-phenylene and the like), mercapto-1,2-phenylene (such as 4-mercaptop-1,2-phenylene and the like), etherified mercapto-1,2-phenylene, such as lower alkyl-mercapto-1,2-phenylene, e.g. methylmercapto-1,2-phenylene (such as 4-methylmercapto-1,2-phenylene and the like), ethylmercapto-1,2-phenylene (such as 3-ethylmercapto-1,2-phenylene and the like), or any other analogous lower alkyl-mercapto-1,2-phenylene radical, nitro-1,2-phenylene (such as 3-nitro-1,2-phenylene, 4-nitro-1,2-phenylene and the like), N,N-di-lower alkyl-amino-1,2-phenylene, e.g. N,N-dimethylamino-1,2-phenylene (such as 3-N,N-dimethylamino-1,2-phenylene, 4-N,N-dimethylamino-1,2-phenylene and the like), N-ethyl-N-methyl-amino-1,2-phenylene (such as 4-N-ethyl-N-methyl-amino-1,2-phenylene and the like), N,N-diethylamino-1,2-phenylene (such as 4-N,N-diethylamino-1,2-phenylene and the like), or any other N,N-di-lower alkyl-amino-1,2-phenylene radical, N-acyl-amino-1,2-phenylene, such as N-lower alkanoyl-amino-1,2-phenylene, e.g. N-acetylamino-1,2-phenylene (such as 4-N-acetyl-amino-1,2-phenylene and the like), N-

pivaloylamino-1,2-phenylene (such as 4-N-pivaloylamino-1,2-phenylene and the like), as well as N-benzoylamino-1,2-phenylene (such as 4-N-benzoylamino-1,2-phenylene and the like), or any other analogous N-acyl-amino-1,2-phenylene radical, or particularly acyl-1,2-phenylene, such as lower alkanoyl-1,2-phenylene, e.g. acetyl-1,2-phenylene (such as 3-acetyl-1,2-phenylene, 4-acetyl-1,2-phenylene and the like), propionyl-1,2-phenylene-1,2-phenylene (such as 3-propionyl-1,2-phenylene and the like), butyryl-1,2-phenylene (such as 4-butyryl-1,2-phenylene and the like), pivaloyl-1,2-phenylene (such as 3-pivaloyl-1,2-phenylene and the like) or any other analogous lower alkanoyl-1,2-phenylene radical, monocyclic carbocyclic aroyl-1,2-phenylene, e.g. benzoyl-1,2-phenylene (such as 3-benzoyl-1,2-phenylene, 4-benzoyl-1,2-phenylene and the like) or any other analogous monocyclic carbocyclic aroyl-1,2-phenylene radical, monocyclic carbocyclic aryl-lower alkanoyl-1,2-phenylene, such as phenyl-lower alkanoyl-1,2-phenylene, e.g. phenylacetyl-1,2-phenylene (such as 3-phenylacetyl-1,2-phenylene and the like) or any other analogous monocyclic aryl-lower alkanoyl-1,2-phenylene radical, or any equivalent substituted 1,2-phenylene radical.

The alkylene radical represented by $—C_nH_{2n}—$ in the above formula, in which n may stand for a whole number from one to seven, has preferably from one to four carbon atoms (n stands, therefore, preferably for a whole number from one to four), which carbon atoms may be arranged in a straight or a branched carbon chain. Such alkylene radicals may be represented by methylene, 1,1-ethylene, 1,2-ethylene, 1-methyl-1,2-ethylene, 2-methyl-1,2-ethylene, 1,3-propylene, 1,4-butylene and the like, as well as 1,4-pentylene, 1,5-pentylene, 1,6-hexylene, 1,7-heptylene and the like.

The cycloaliphatic radical R_2 is preferably saturated and represents, therefore, primarily cycloalkyl. However, it may also contain one or more than one double bond, depending on the number of ring carbon atoms. A cycloalkyl group may have from three to eight, preferably from five to six, ring carbon atoms. Cycloalkyl is, therefore, primarily cyclopentyl or cyclohexyl, as well as cyclopropyl, cyclobutyl, cycloheptyl or cyclo-octyl. A cycloaliphatic radical having one or more than one double bond is particularly a cycloalkenyl group, which has from five to eight, preferably from five to six, carbon atoms; cycloalkenyl groups are, for example, 1-cyclopentenyl, 2-cyclopentenyl, 3-cyclopentenyl, 1-cyclohexenyl, 2-cyclohexenyl, 3-cyclohexenyl and the like, as well as 3-cycloheptenyl, 2-cyclo-octenyl and the like. The cycloaliphatic radicals are preferably unsubstituted, but may contain substituents, such as, for example, lower alkyl, e.g. methyl, ethyl, n-propyl, isopropyl and the like, or functional groups, such as halogeno, e.g. chloro, bromo and the like, lower alkoxy, e.g. methoxy, ethoxy and the like, or any other suitable functional group.

Salts of the new compounds of this invention are particularly non-toxic, pharmaceutically acceptable acid addition salts, for example, those with inorganic acids, e.g. hydrochloric, hydrobromic, sulfuric, phosphoric acids and the like, with organic carboxylic acids, e.g. formic, acetic, propionic, glycolic, lactic, pyruvic, oxalic, malonic, succinic, maleic, fumaric, malic, tartaric, citric, ascorbic, hydroxymaleic, dihydroxymaleic, benzoic, phenylacetic, 4-aminobenzoic, 4-hydroxybenzoic, cinnamic, mandelic, salicyclic, 4-aminosalicyclic, 2-phenoxybenzoic, 2-acetoxybenzoic acid and the like, or with organic sulfonic acids, e.g. methane sulfonic, ethane sulfonic, 2-hydroxyethane sulfonic, ethane 1,2-disulfonic acid, benzene sulfonic, p-toluene sulfonic acid and the like.

The compounds of this invention have long-lasting antihypertensive properties and can, therefore, be used as antihypertensive agents, for example, in renal hypertension or similar hypertensive conditions. Apart from some atoxic properties, the compounds of this invention are virtually free from adverse side effects usually associated

with antihypertensive compounds, such as, for example, adrenolytic properties; thus, they do not affect the motility of the intestine or the gastric secretion, and do not produce tachycardia.

A preferred group of compounds, which show strong long-lasting antihypertensive properties may be represented by the formula

15

in which R_2' represents cycloalkyl having from three to eight carbon atoms and stands primarily for cyclopentyl or cyclohexyl, n' represents a whole number from one to four, and the pharmaceutically acceptable acid addition salts of such compounds.

20

Another group of compounds, which have outstanding and long-lasting antihypertensive effects and are virtually free from any unwarranted adrenolytic side effects, is represented by the formula

30

35

in which R_2' and the letter n' have the previously-given meaning, and in which R_3 stands for lower alkanoyl, and the pharmaceutically acceptable acid addition salts thereof. This group of compounds may be represented by benz-acetyl-2-(N-cycloalkyl-lower alkyl-amino-methyl)-1,4-benzodioxanes, in which cycloalkyl has from five to six ring carbon atoms, lower alkyl has from one to four carbon atoms, and acetyl is attached to the carbocyclic aryl portion of the 1,4-benzodioxane nucleus, or pharmaceutically acceptable acid addition salts thereof.

40

45

50

55

The new compounds of this invention may be used in the form of pharmaceutical preparations, which contain the new compounds or the salts thereof in admixture with a pharmaceutical organic or inorganic, solid or liquid carrier suitable for enteral or parenteral administration. For making up the preparations there are employed substances which do not react with the new compounds, such as water, gelatine, lactose, starches, stearic acid, magnesium stearate, stearyl alcohol, talc, vegetable oils, benzyl alcohols, gums, propylene glycol, polyalkylene glycols, petroleum jelly or any other known carrier used for pharmaceutical preparations. These may be in solid form, for example, as tablets, dragees, capsules and the like, or in liquid form, for example, as solutions, suspensions, emulsions and the like, and, if desired, may contain auxiliary substances, such as preserving, stabilizing, wetting, emulsifying agents and the like, salts for varying the osmotic pressure, buffers, etc. They may also contain, in combination, other pharmaceutically useful substances.

60

65

70

75

The compounds of this invention may be prepared according to methods known per se. I prefer to manufacture these compounds by treating a cycloaliphatic hydrocarbon-lower alkyl-amine, particularly an amine of the formula $R_2-(C_nH_{2n})-NH_2$, in which R_2 and the letter n have the previously-given meaning, with a reactive ester of a 2-(1,4-benzodioxanyl)methanol, particularly with a compound of the formula R_1-CH_2-X , in which R_1 has the previously-given meaning, and X represents a reactive esterified hydroxyl group, and, if desired, converting a resulting salt into a free compound or into another salt, and/or, if desired, converting a free compound into a salt thereof, and/or, if desired, introducing a substituent into the carbocyclic aryl portion of the 1,4-benzodioxane nucleus, and/or, if desired, converting a substituent attached to the carbocyclic aryl portion of the 1,4-benzodioxane nucleus into another substituent.

A reactive esterified hydroxyl group, such as the group X is a reactive ester of a 2-(1,4-benzodioxanyl)methanol,

such as a compound of the formula R_1-CH_2-X , is particularly a hydroxyl group esterified with a strong inorganic acid, such as a mineral acid, particularly a hydrohalic acid, e.g. hydrochloric, hydrobromic, hydroiodic acid and the like, as well as sulfuric acid and the like, or a strong organic acid, particularly a strong organic sulfonic acid, such as a monocyclic carbocyclic aryl sulfonic acid, e.g. p-toluene sulfonic acid and the like, or a lower alkane sulfonic acid, e.g. methane sulfonic acid, ethane sulfonic acid and the like. The group X in the above formula is primarily represented by halogeno having an atomic weight greater than 19, such as chloro, bromo or iodo.

The reaction is preferably carried out by treating the amine with the reactive ester of the 2-(1,4-benzodioxanyl)-methanol compound in such a way that an excess of the amine is always present. Alcohols, such as lower alkanols, e.g. methanol, ethanol and the like, or any other suitable inert diluent may serve as solvents. If necessary, an alkaline reagent, such as an alkali metal carbonate, e.g. sodium or potassium carbonate and the like, or an organic base, e.g. pyridine and the like, may be used to neutralize the generated acid.

The reaction is preferably performed at an elevated temperature, if necessary, in a closed vessel under pressure and/or in the atmosphere of an inert gas, e.g. nitrogen.

The starting materials used in the above reaction are known or may be prepared according to methods used for the preparation of the known compounds.

The compounds of this invention may also be prepared by reacting a 2-(1,4-benzodioxanyl)methyl-amine, particularly a compound of the formula $R_1-CH_2-NH_2$, in which R_1 has the previously-given meaning, with a reactive ester of a cycloaliphatic hydrocarbon-lower alkanol, particularly with a compound of the formula $R_2-(C_nH_{2n})-X$, in which R_2 , X and the letter n have the previously-given meaning, and, if desired, carrying out the optional steps.

This reaction is carried out according to the previously-described procedure; the starting materials are known or may be prepared according to procedures used for the known compounds.

The compounds of this invention may also be obtained by converting in a 1,4-benzodioxane 2-carboxylic acid cycloaliphatic-lower alkyl-amide, particularly in a compound of the formula $R_1-CO-NH-(C_nH_{2n})-R_2$, in which R_1 , R_2 and n have the previously-given meaning, the carbonyl group into methylene, and, if desired, carrying out the optional steps.

Conversion of the carbonyl portion of the amide group into methylene is carried out according to known methods, particularly by treatment with a reducing reagent capable of converting the carbonyl portion of the amide grouping into methylene. Such reducing agents are especially alkali metal aluminum hydrides or alkaline earth metal aluminum hydrides, particularly lithium aluminum hydride, as well as sodium aluminum hydride, magnesium aluminum hydride and the like; if desired, these reagents may be used in the presence of an activator, for example, aluminum chloride and the like. The reaction is carried out in the presence of a suitable solvent, for example, an ether, e.g. diethyl ether, tetrahydrofuran and the like, and, if necessary, at an elevated temperature, for example, at the refluxing temperature of the solvent. The amine may also be obtained by electrolytically reducing the amide on a suitable cathode, such as mercury, lead, nickel cathode and the like, using a proper anode and suitable catholyte and anolyte media. Conversion of the carbonyl portion in an amide group into methylene may also be carried out by treatment with hydrogen in the presence of a suitable catalyst, e.g. certain copper catalysts and the like.

The starting materials used in the above reaction may be prepared according to procedures generally used for the preparation of carboxylic acid amides, for example,

by treatment of an acid halide, e.g. chloride, with an amine.

Compounds of this invention, particularly those of the formula

5 $R_1-CH_2-NH-CH_2-(C_{n-1}H_{2n-2})-R_2$
in which R_1 , R_2 and the letter n have the previously-given meaning, or salts thereof, may also be obtained by converting in a cycloaliphatic hydrocarbon-carboxylic acid 2-(1,4-benzodioxanyl)-methyl-amide or in a cycloaliphatic hydrocarbon-lower alkane carboxylic acid 2-(1,4-benzodioxanyl)-methyl-amide, particularly in a compound having the formula

10 $R_1-CH_2-NH-CO-(C_{n-1}H_{2n-2})-R_2$
in which R_1 , R_2 and the letter n have the previously-given meaning, the carbonyl group into methylene, and, if desired, carrying out the optional steps.

The above reaction is carried out according to the previously-described methods, and the starting materials are prepared according to known procedures.

The compounds of the present invention may also be prepared by converting in a 1,4-benzodioxane 2-thiocarboxylic acid cycloaliphatic hydrocarbon-lower alkyl-amide, particularly in a compound of the formula

25 $R_1-CS-NH-(C_nH_{2n})-R_2$
in which R_1 , R_2 and the letter n have the previously-given meaning, the thiocarbonyl group into methylene, and, if desired, carrying out the optional steps.

30 The above conversion may be carried out according to known methods, for example, by treating the thiocarbonyl compound with freshly prepared Raney nickel in a suitable, particularly in an alcoholic, solvent, e.g. methanol, ethanol and the like, or electrolytically reducing it according to the procedure outlined hereinabove for the reduction of the amides.

The starting materials may be prepared, for example, from the previously-described amides by treatment with suitable reagents, e.g. phosphorus pentasulfide and the like.

Another method for the preparation of compounds of this invention, particularly of compounds having the formula

45 $R_1-CH_2-NH-CH_2-(C_{n-1}H_{2n-2})-R_2$
in which R_1 , R_2 and the letter n have the previously-given meaning, comprises converting in a cycloaliphatic hydrocarbon thiocarboxylic acid 2-(1,4-benzodioxanyl)-methyl-amide or in a cycloaliphatic hydrocarbon-lower alkane thiocarboxylic acid 2-(1,4-benzodioxanyl)-methyl-amide, particularly in a compound having the formula

50 $R_1-CH_2-NH-CS-(C_{n-1}H_{2n-2})-R_2$
in which R_1 , R_2 and the letter n have the previously-given meaning, the thiocarbonyl group into methylene, and, if desired, carrying out the optional steps.

The above procedure is carried out as shown hereinbefore, and the starting material is prepared according to known methods.

60 Compounds of this invention, particularly those of the formula

55 $R_1-CH_2-NH-CH_2-(C_{n-1}H_{2n-2})-R_2$
in which R_1 , R_2 and the letter n have the previously-given meaning, or salts thereof, may also be obtained by removing in an $N-[2-(1,4-benzodioxanyl)-methyl]-N$ -cycloaliphatic hydrocarbon-lower alkylidene-amine, particularly in a compound of the formula

65 $R_1-CH_2-N=CH-(C_{n-1}H_{2n-2})-R_2$
in which R_1 , R_2 and the letter n have the previously-given meaning, the Schiff base-type C=N-double bond by reduction, and, if desired, carrying out the optional steps.

The reduction of the Schiff base-type double bond may

be carried out by using catalytically activated hydrogen or a di-light metal hydride as hydrogenating agents. Catalysts containing a metal of the eighth group of the Periodic System may be used in the presence of hydrogen; for example, palladium, e.g. palladium on charcoal and the like, represents a suitable metal catalyst. The reduction is carried out by treating, for example, a lower alkanol, e.g. methanol, ethanol and the like, solution of the Schiff base with hydrogen, if desired, at an increased pressure, in the presence of the catalyst.

The preferred reduction reagents, however, are light metal hydrides, particularly the alkali metal borohydrides, e.g. lithium borohydride, sodium borohydride and the like, as well as alkali metal aluminum hydrides, e.g. lithium aluminum hydride, sodium aluminum hydride and the like, alkaline earth metal aluminum hydrides, e.g. magnesium aluminum hydride and the like, or any other suitable light metal hydride. The reduction with these reagents is preferably carried in solution, the solvents being chosen according to the reactivity of the reagent. For example, an alcohol, such as a lower alkanol, e.g. methanol, ethanol, isopropanol and the like, if desired, aqueous mixtures thereof, and the like may be used with an alkali metal borohydride; an ether, e.g. diethylether, tetrahydrofuran and the like, is used with an alkali metal aluminum hydride. If desired, the reaction may be promoted by the addition of an activator, for example, of aluminum chloride and the like. The reaction is performed at room temperature or preferably at an elevated temperature, for example, at the boiling temperature of the solvent, and, if necessary, in the atmosphere of an inactive gas, e.g. nitrogen.

The Schiff base-type starting materials may be prepared according to methods known per se, for example, by reacting a 2-benzodioxanyl-methyl-amine with a cycloaliphatic hydrocarbon carboxaldehyde or with a cycloaliphatic hydrocarbon-lower alkane carboxaldehyde, if necessary, in the presence of a solvent, such as an alcohol, for example, a lower alkanol, e.g. methanol, ethanol and the like, and/or under cooling at room temperature or at an elevated temperature.

The compounds of this invention may also be prepared by removing in an N-[2-(1,4-benzodioxanyl)-methylene]-N-cycloaliphatic hydrocarbon-lower alkyl-amine, particularly in a compound of the formula

in which R_1 , R_2 and the letter n have the previously-given meaning, the Schiff base-type C=N-double bond by reduction, and, if desired, carrying out the optional steps.

The reductive removal of the Schiff base-type double bond is carried out as previously shown; the starting material is prepared according to known methods.

Depending on the conditions used in new compounds of this invention may be obtained in the form of the free bases or as the salts thereof. A salt may be converted into the free base in the customary way, for example, by reaction with an alkaline reagent, such as an alkali metal hydroxide, e.g. sodium hydroxide, potassium hydroxide and the like, an alkali metal carbonate, e.g. sodium or potassium carbonate or hydrogen carbonate and the like, ammonia and the like, or with a suitable anion exchange resin. A free base may be converted into an acid addition salt by reacting it or a solution thereof in a suitable solvent with the appropriate inorganic or organic acid, such as one of those outlined hereinbefore, or a solution thereof. Salts may also be converted into other salts directly; for example, a hydrobromic may be converted into the hydrochloride or maleate by treating an aqueous solution of the former with an alkali metal chloride, e.g. sodium chloride and the like, or with a mono-alkali metal salt of maleic acid, e.g. mono-sodium maleate and the like, and isolating the desired salt.

The invention also comprises any modification of the process wherein a compound obtainable as an intermediate

diate at any stage of the process is used as starting material and the remaining step(s) of the process is(are) carried out, as well as any new intermediates.

In the process of the invention such starting materials are preferably used which lead to final products mentioned in the beginning as preferred embodiments of the invention.

This is a continuation-in-part application of my application Serial No. 142,507, filed October 3, 1961, which in turn is a continuation-in-part application of my application Serial No. 103,210, filed April 17, 1961, both now abandoned.

The following examples are intended to illustrate the invention and are not to be construed as being limitations thereon. Temperatures are given in degrees centigrade.

Example 1

A mixture of 4.52 g. of cyclopentylethylamine and 2.5 g. of 2-chloromethyl-1,4-benzodioxane in 15 ml. of ethanol is heated in a sealed tube for four hours to 150°. After cooling, the reaction mixture is concentrated under reduced pressure, the residue is dissolved in ethyl acetate, and the organic solution is washed with water and dried over sodium sulfate. A solution of hydrogen chloride in ethyl acetate is added to precipitate the 2-[2-(2-cyclopentylethyl)-aminomethyl]-1,4-benzodioxane hydrochloride of the formula

which is recrystallized from ethanol, M.P. 250-252°; yield: 36 percent.

Example 2

A mixture of 4.75 g. of cyclopentylmethylamine and 2.9 g. of 2-chloromethyl-1,4-benzodioxane in 15 ml. of ethanol is reacted according to the method shown in Example 1 to yield the 2-(cyclopentylmethylaminomethyl)-1,4-benzodioxane hydrochloride of the formula

which melts at 217–219°; yield: 42 percent.

Example 3

A mixture of 9.6 g. of 3-cyclopentylpropylamine and 4.2 g. of 2-chloromethyl-1,4-benzodioxane in 25 ml. of ethanol, when reacted as described in Example 1, yields the 2-[(3-cyclopentylpropyl)-aminomethyl]-1,4-benzodioxane hydrochloride of the formula

which melts at 245–246°; yield: 64 percent.

Example 4

A mixture of 9.0 g. of 2-cyclohexylethylamine and 3.8 g. of 2-chloromethyl-1,4-benzodioxane in 20 ml. of ethanol, when heated in a sealed tube and worked up according to the method shown in Example 1, yields the 2-[(2-cyclohexylethyl)-aminoethyl]-1,4-benzodioxane hydrochloride of the formula

which melts at 263–265°; yield: 72 percent.

Example 5

A mixture of 8.5 g. of 3-cyclohexylpropylamine and 3.7 g. of 2-chloromethyl-1,4-benzodioxane in 20 ml. of ethanol yields the 2-[3-cyclohexylpropyl]-aminomethyl]-1,4-benzodioxane hydrochloride of the formula

when reacted according to the procedure of Example 1, and melts at 234-237°; yield: 71 percent.

Example 6

A mixture of 3.7 g. of 2-chloromethyl-1,4-benzodioxane and 8.4 g. of 2-cycloheptylethyl-amine in 15 ml. of ethanol is reacted as shown in Example 1; the resulting 2-[2-cycloheptylethyl]-aminomethyl]-1,4-benzodioxane hydrochloride melts at 247-251°; yield: 2.5 g.

Example 7

A solution of 3.0 g. of a mixture of 2-chloromethyl-5-methoxy-1,4-benzodioxane and 2-chloromethyl-8-methoxy-1,4-benzodioxane and 4.8 g. of 2-cyclopentylethyl-amine in 15 ml. of ethanol is heated in a sealed tube to 150° for four hours. The reaction mixture is concentrated and taken up in diethylether and water. The organic solution is separated, washed, dried and evaporated. The residue is dissolved in ethyl acetate, anhydrous hydrogen chloride as passed through the solution and the precipitate is collected. The resulting compound is the 2-[2-cyclopentylethyl]-aminomethyl]-8-methoxy-1,4-benzodioxane hydrochloride, M.P. 161-165°; yield: 1.7 g.

Example 8

A solution of 8.2 g. of 2-[2-cyclopentylethyl]-aminomethyl]-8-methoxy-1,4-benzodioxane hydrochloride in 25 ml. of aqueous hydrobromic acid of 48 percent strength is slowly heated to 125° allowing any methyl bromide to distill off. The reaction mixture is cooled, the resulting solid material is filtered off and washed with acetone to yield 5.6 g. of the crude 2-[2-cyclopentylethyl]-aminomethyl]-8-hydroxy-1,4-benzodioxane hydrobromide, M.P. 297° (decomposition).

A chloroform slurry of the above hydrobromide salt is treated with sodium hydrogen carbonate, the organic solution is washed with water, dried and concentrated. On cooling, the free 2-[2-cyclopentylethyl]-aminomethyl]-8-hydroxy-1,4-benzodioxane crystallizes, is triturated with diethyl ether and filtered off, M.P. 135-137°; yield: 3.3 g. The hydrochloride is prepared by treating an ethanol solution of the free base with anhydrous hydrogen halide. The 2-[2-cyclopentylethyl]-aminomethyl]-8-hydroxy-1,4-benzodioxane hydrochloride melts above 275°; yield: 3.3 g.

Example 9

A solution of 4.4 g. of a mixture of 5-benzyloxy-2-chloromethyl-1,4-benzodioxane and 8-benzyloxy-2-chloromethyl-1,4-benzodioxane and 5.1 g. of 2-cyclopentylethylamine in 25 ml. of ethanol is heated in a sealed tube to 150° for four hours; the reaction mixture is worked up as shown in Example 1. The hydrochloride is prepared by passing anhydrous hydrogen chloride through a solution of the free base in ethyl acetate. 2.6 g. of 5-benzyloxy-2-[2-cyclopentylethyl]-aminomethyl]-1,4-benzodioxane hydrochloride precipitates and is recrystallized from isopropanol, M.P. 218-220°; yield: 0.9 g. The ethyl acetate mother liquor is allowed to stand and yields 1.1 g. of 8-benzyloxy-2-[2-cyclopentylethyl]-aminomethyl]-1,4-benzodioxane hydrochloride, which is recrystallized from isopropanol, M.P. 179-180°.

The starting materials may be prepared as follows: A mixture of 10.0 g. of a mixture of 2-chloromethyl-5-hydroxy-1,4-benzodioxane and 2-chloromethyl-8-hydroxy-

1,4-benzodioxane, 12.8 g. of benzyl bromide and 10.4 g. of anhydrous potassium carbonate in 50 ml. of acetone is refluxed for twenty hours while stirring. After cooling, the reaction mixture is diluted with 250 ml. of water, the 5 organic material is extracted with diethyl ether and the latter solution is washed with 10 percent aqueous solution of sodium hydroxide and water. After drying, the solvent is evaporated, and the residue is distilled to yield 8.9 g. of a mixture of 5-benzyloxy-2-chloromethyl-1,4-benzodioxane and 8-benzyloxy-2-chloromethyl-1,4-benzodioxane, B.P. 182-185°/0.6 mm.

Example 10

A solution of 7.1 g. of the mixture of two isomeric benz-acetyl-2-chloromethyl-1,4-benzodioxanes and 10.5 g. of 2-cyclopentylethyl-amine in 50 ml. of ethanol is heated in a sealed tube for four hours at 150°. The reaction mixture is concentrated, water and diethylether are added; the organic phase is separated, washed with water, dried and evaporated to dryness. The residue is dissolved in ethyl acetate, dry hydrogen chloride is added and the resulting crude product is filtered off and extracted with isopropanol; after cooling, 3.6 g. of a solid material is isolated and recrystallized from ethanol to yield 1.0 g. of benz-acetyl-2-(2-cyclopentylethyl-aminomethyl)-1,4-benzodioxane (isomer I) hydrochloride, M.P. 217-219°.

The isopropanol filtrate is evaporated to dryness, the residue is extracted with water, and the mixture is cooled, whereupon an oil separates. The latter is extracted with ethyl acetate the aqueous solution is made alkaline with sodium hydroxide, and the organic material is extracted with ethyl acetate. The organic solution is dried and evaporated, and the residue is distilled; yield: 0.8 g. of benz-acetyl-2-(2-cyclopentylethyl-aminomethyl)-1,4-benzodioxane (isomer II) of the formula

which is converted into its hydrochloride, M.P. 155-158°, by treating an ethyl acetate solution of the free base with a concentrated solution of hydrogen chloride in ethyl acetate.

The starting material may be prepared as follows: To a solution of 18.5 g. of 2-chloromethyl-1,4-benzodioxane and 9.0 g. of acetyl chloride in 70 ml. of carbon disulfide is added 13.3 g. of aluminum chloride over a period of thirty minutes while stirring. After the evolution of hydrogen chloride has slowed down, the reaction mixture is heated on the steam bath for thirty minutes and is then cooled and treated with a mixture of ice and water. The water and carbon disulfide layer are decanted from the solid material which is taken up in diethyl ether and water. The organic solution is then separated, washed with water, dried and evaporated. The residue is distilled under reduced pressure to yield 7.1 g. of a mixture of two isomeric benz-acetyl-1,4-benzodioxanes, which is collected at 148°/0.5 mm., and is used without separating the isomeric compounds.

Other compounds, such as, for example, 2-(cyclopropylmethylaminomethyl)-benzodioxane, 2-[2-cyclopropylethyl]-aminomethyl-benzodioxane, 2-[2-cyclobutylethyl]-aminomethyl-benzodioxane, 2-(cycloheptylmethylaminomethyl)-benzodioxane, 2-[2-cycloheptylethyl]-aminomethyl-benzodioxane, 2-[2-cyclooctylethyl]-aminomethyl]-3-methyl-benzodioxane, 2-(cyclopentylmethylaminomethyl)-5-methyl-benzodioxane, 2-[2-cyclopentylethyl]-aminomethyl]-8-ethoxy-benzodioxane, 2-(cyclohexylmethylaminomethyl)-5-chloro-benzodioxane, 2-[2-cyclohexylethyl]-aminomethyl]-8-methoxy-benzodioxane, 2-[2-(1-cyclohexenyl)-ethyl]-aminomethyl-benzodioxane, 2-[2-(1-cycloheptenyl)-ethyl]-aminomethyl]-benzodioxane and the like, or salts thereof, may be prepared according to the above procedure.

11
Example 11

A mixture of 6.6 g. of 7-acetyl-2-(4-bromo-phenylsulfonyloxy-methyl)-1,4-benzodioxane, 66 ml. of acetonitrile and 3.3 g. of 2-cyclopentylethylamine is refluxed for 19 hours. After cooling, the precipitate is filtered off, and the filtrate is evaporated to dryness. The residue is dissolved in ethyl acetate, a small amount of insoluble material is filtered off and the filtrate is treated with a small amount of a concentrated solution of hydrogen chloride in dry ethyl acetate. The crystalline 7-acetyl-2-[(2-cyclopentylethyl)aminomethyl]-1,4-benzodioxane hydrochloride of the formula

precipitates; it melts at 156-160° (yield: 3.5 g.) and is identical with the hydrochloride of the benz-acetyl-2-[(2-cyclopentylethyl) - aminomethyl]-1,4-benzodioxane (isomer II) of Example 10.

The starting material used in the above procedure is prepared as follows: To a solution of 39.9 g. of sodium hydroxide in 345 ml. of water is added 69 g. of 3,4-dihydroxy-acetophenone, the solution is cooled to -5° while maintaining an atmosphere of nitrogen. Over a period of ninety minutes, a solution of 95 g. of phosgene in 400 ml. of toluene is added dropwise while maintaining the temperature of the reaction mixture at 0°. After about one-half of the phosgene solution has been added, the pH of the solution has become neutral; an additional solution of 20 g. of sodium hydroxide in 180 ml. of water is, therefore, added in portions. Upon completion of the phosgene addition, the reaction mixture is stirred for one hour in an ice-bath, and is then filtered; the two layers are separated, and the toluene solution is evaporated to dryness. The residue is combined with the solid material previously filtered off. The crude product is extracted twice with about 200 ml. of ethanol at room temperature to yield 58 g. of 4-acetyl-o-phenylene carbonate, M.P. 108-110.5°.

A mixture of 50 g. of 4-acetyl-o-phenylene carbonate in 500 ml. of methanol is refluxed for three hours while stirring. The solvent is removed under reduced pressure and the residue is allowed to crystallize. The desired 3-acetyl-6-hydroxy-phenyl methyl carbonate is recrystallized by dissolving it in isopropanol while heating and diluting the solution with two volumes of hexane, M.P. 127-129°; yield: 41.3 g.

A mixture of 32 g. of 3-acetyl-6-hydroxy-phenyl methyl carbonate, 42.2 g. of epichlorohydrin and 0.3 ml. of piperidine is heated for one hour on the steam bath; an additional five drops of piperidine is added, heating is continued, and after one hour, again five drops of piperidine are added. After a total heating time of seven hours, the unreacted epichlorohydrin is removed by distillation under reduced pressure; the residue is dissolved in chloroform and 20 ml. of concentrated hydrochloric acid are added. After standing for 4½ hours at room temperature with occasional agitation, the organic solution is separated, washed twice with water, dried and concentrated under reduced pressure. The residue is dissolved in 50 ml. of ethanol and added to a solution of 30 g. of potassium hydroxide in 60 ml. of water. The reaction mixture becomes warm, and potassium chloride precipitates. After standing at room temperature for thirty minutes, ethyl acetate is added, and the resulting solution is washed twice with 200 ml. of water. After drying over sodium sulfate, the solution is evaporated to dryness; the oily residue is dissolved in 50 ml. of ethanol and on standing, the 3,4-bis-(2,3-epoxypropyl-oxy)-acetophenone precipitates and is filtered off, yield: 70

8.6 g. The pure product melts at 94-96° after recrystallization from ethanol.

The ethanol mother liquors are concentrated and the residue is distilled under reduced pressure; the desired 7-acetyl-2-hydroxymethyl-1,4-benzodioxane is collected at 176°/0.1 mm.; yield: 14 g.

A solution of 4.0 g. of 7-acetyl-2-hydroxymethyl-1,4-benzodioxane in 20 ml. of pyridine is treated with 6.4 g. of p-bromo-benzene sulfonyl chloride. The reaction mixture is allowed to stand at room temperature over night and is then poured onto a mixture of ice and water. The aqueous layer is decanted; the oily precipitate is dissolved in chloroform and the chloroform solution is washed with dilute hydrochloric acid and water and is dried and concentrated to yield 6.5 g. of the crude product. The latter is repeatedly extracted with 25 ml. portions of hot ethanol; on cooling the desired 7-acetyl-2-(4-bromo-phenyl - sulfonyloxy-methyl)-1,4-benzodioxane crystallizes and is recrystallized from methanol, M.P. 125-127°.

Into the carbocyclic aryl portion of the 1,4-benzodioxane nucleus of a resulting compound, a substituent may be introduced. For example, upon nitration with a suitable nitrating reagent, a nitro group may be introduced. Or, a resulting compound may be reacted with an organic carboxylic acid halide, e.g. chloride and the like, in the presence of a suitable reagent, such as aluminum chloride and the like, and an organic carboxylic acid acyl radical may be introduced.

Certain substituents attached to the carbocyclic aryl portion of the 1,4-benzodioxane nucleus may be converted into other substituents. For example, a nitro group may be reduced to an amino group according to known reduction methods, for example, by controlled treatment with hydrogen in the presence of a suitable catalyst, e.g. palladium on charcoal and the like, and of an inert solvent, e.g. p-dioxane and the like. An amino group may be converted into a halogeno atom by diazotization, followed by treatment with a cuprous halide according to the Sandmeyer reaction. Or, a lower alkoxy, e.g. methoxy and the like, group may be converted into a free hydroxyl group, for example, by acidic hydrolysis with hydrobromic acid in the presence of acetic acid and the like.

What is claimed is:

1. A member selected from the group consisting of a compound of the formula

in which R_2 is a member selected from the group consisting of hydrogen and lower alkyl, the letter n stands for a whole number from one to seven, R_2 stands for a member selected from the group consisting of cycloalkyl having from three to eight ring carbon atoms and cycloalkenyl having from five to eight ring carbon atoms, and Ph stands for a member selected from the group consisting of 1,2-phenylene, lower alkyl-1,2-phenylene, hydroxy-1,2-phenylene, lower alkoxy-1,2-phenylene, phenyl-lower alkoxy-1,2-phenylene, halogeno-1,2-phenylene, and lower alkanoyl-1,2-phenylene, and pharmaceutically acceptable acid addition salts thereof.

2. A compound of the formula

in which R_2' represents cycloalkyl having from three to eight carbon atoms, and the letter n' stands for a whole number from one to four.

13

3. The pharmaceutically acceptable acid addition salt of a compound of the formula

in which R_2' represents cycloalkyl having from three to eight carbon atoms, and the letter n' stands for a whole number from one to four.

4. 2 - [(2 - cyclopentylethyl) - aminomethyl] - benzodioxane.

5. 2-(cyclopentylmethylaminomethyl)-benzodioxane.

6. 2 - [(3 - cyclopentylpropyl) - aminomethyl] - benzodioxane.

7. 2 - [(2-cyclohexylethyl)-aminomethyl]-benzodioxane.

8. 2 - [(3 - cyclohexylpropyl) - aminomethyl] - benzodioxane.

9. A compound of the formula

10

5 of 10
5. The pharmaceutically acceptable acid addition salt of a compound of the formula

in which R_2' represents cycloalkyl having from three to eight carbon atoms, the letter n' stands for a whole number from one to four, and R_3 stands for lower alkanoyl.

11. 7 - acetyl - 2 - [(2-cyclopentylethyl)-aminomethyl]-1,4-benzodioxane.

12. 7 - acetyl - 2 - [(2-cyclopentylethyl)-aminomethyl]-1,4-benzodioxane hydrochloride.
